HYDROFOIL CRAFT

Glenford Joseph Wennagel, Huntington, and August C. Sarrantoni, Huntington Station, N.Y., assignors to Grumman Aircraft Engineering Corporation, Bethpage, N.Y., a corporation of New York

Filed Feb. 4, 1963, Ser. No. 255,832
9 Claims. (Cl. 114—66.5)

This invention relates to improvements in hydrofoil craft and, in particular, relates to means for automatically adjusting the lift characteristics of the hydrofoils for achieving proper depth control of the hydrofoils.

Hydrofoil craft are generally provided with submerged hydrofoils or supporting fins inclined at a suitable angle of incidence so that upon the craft attaining a predetermined speed it is supported above its normal floating position at a distance above the water surface by the lift generated by the submerged hydrofoils.

There are several methods for controlling the depth of submergence of the hydrofoils to regulate the clearance of the hull of the hydrofoil craft above the water. As is well known in the art, where hydrofoils of the surface-piercing type are used, depth control is effected through the shape of the hydrofoil itself, in that lift is dependent on depth of submergence.

The same principle is sometimes used by arranging an array of lifting surfaces at different superimposed levels such that the number of surfaces submerged increases with the depth of submergence so to thereby increase the lift.

Because of a number of inherent disadvantages of such arrangement, submerged hydrofoil systems using hydrofoil sets and some means for depth control are increasingly employed in the art.

It has already been proposed in craft of the submerged hydrofoil type that an autopilot be used to control the angle of attack of the hydrofoil or the position of a flap associated with the hydrofoil to thereby control the lift and hence the depth of submergence of the hydrofoil. However, because of the complexity required in the design of such systems to insure the levels of effectiveness and reliability in autopilots for this service, their cost and maintenance requirements have militated against their use.

Another approach proposed in the prior art to this problem of depth control has been the provision of a control plane or float which floats or skims on the surface of the water and which is normally disposed ahead of the hydrofoil which it controls. The object of the control plane or float is to predict the wave formation ahead of the craft and by suitable linkage to vary the lift of the hydrofoil by varying its angle of attack or by actuating a flap associated with the hydrofoil. The disadvantages of this known system of water surface prediction are the vulnerability of the jockey arms usually employed in the mechanical linkage, as well as in the design difficulties posed in incorporating an effective hydrofoil retraction mechanism with such an arrangement. Furthermore, at speed, the control planes or floats are found to impact and bounce on the waves causing objectionable levels of shock, vibration, and noise in the craft. Should the wave structure result in severe bouncing of the control means, the consequent fluctuations induced in the lift of the hydrofoils adversely affects the stability of the craft.

It has also been proposed in craft of this kind to utilize water pressure or depth sensitive means located in fixed structure ahead of the craft or in the hydrofoil structure itself as wave and depth predictor means. Such predictor means serve to regulate a suitable hydrofoil control mechanism to vary the lift of one or more of the hydrofoils such that the craft follows the undulations of the water

2

surface. Such known predictor means employ electrical or other suitable regulating systems to actuate the hydrofoil controls in response to signals from the pressure sensors. By their very nature, these pressure sensors must be relatively sensitive devices and are thus vulnerable to damage by waterborne debris and marine matter. They also introduce an element of complexity in the control system that increases the first cost and maintenance expenses of the craft as well as reducing its reliability.

10 It is thus the principal object of this invention to provide a mechanically simple hydrofoil depth control system to overcome the above mentioned disadvantages of the prior art systems and to achieve novel automatic depth control means for maintaining the depth of submergence of the hydrofoil at the desired or design level such that the hydrofoil operates at a substantially constant depth throughout a range of craft speeds.

15 It is a further object of this invention to provide a fully-automatic hydrofoil depth control system for maintaining the hull of the craft at the desired height above the water surface in foil-borne operation and, in the case of waves, for maintaining a substantially constant submergence of the hydrofoils below an average water level so that smooth transit is obtainable in rough water.

20 Another object of this invention is to provide a hydrofoil depth control system which utilizes surface-piercing controller vane means to obtain a dynamic response to craft speed and sea state and in which the energy required for operation of the mechanism is derived from the energy of the travelling craft such that a separate or an auxiliary power supply for the system is not required.

25 A still further object is to provide a hydrofoil craft with a hydrofoil depth control system wherein the hydrofoils or at least a portion thereof are mounted for varying the lift characteristics of the hydrofoil and including means responsive to the drag forces of the water thereon for controlling the position of the hydrofoils or such lift varying portions.

30 It is another object to provide a novel automatic hydrofoil depth control system which uses rugged, uncomplicated mechanical means to control the lift of the hydrofoil and in which fabrication, installation, and maintenance costs are substantially reduced without any compromise in performance or reliability in either normal or in extremes of operational and environmental conditions.

35 Still another object of this invention is the provision of an automatic hydrofoil depth control system which can be readily accommodated in the engineering design of the hydrofoil retraction system.

40 Another object of this invention is to provide an automatic hydrofoil depth control system whose design permits the incorporation of means for selectively overriding the automatic control system as desired.

45 Other objects and advantages will become apparent from the following description when taken in conjunction with the accompanying drawings in which:

FIG. 1 is a perspective view of one of the hydrofoils of the craft from the outside and rear showing the depth control mechanism;

FIG. 2 is a side view showing the hydrofoil below the design depth of submergence;

FIG. 3 is a side view showing the hydrofoil at the design depth of submergence;

FIG. 4 is a side view of the hydrofoil depth control override mechanism.

50 Referring to the drawings, the instant invention is shown fitted on a hydrofoil craft having a hull 10 on which is mounted the hydrofoil 11 by means of a downwardly depending strut member 12 of suitable streamline shape. As is well known in the art, one or more hydrofoils 11 are provided for the dynamic support of the craft, after it gets under way, such that the hull 10

is raised entirely out of the water. When the craft is in foil-borne operation at its design speed, the clearance above the water surface is adequate in average sea states to avoid substantial wave impact against any portion of the hull. The particular configuration or design of the hull, or the arrangement or number of hydrofoils employed are not shown and will not be described in detail since such form no part of the instant invention. The craft also may be driven or steered in any suitable way such as by air or water screws and rudders, which again do not form part of the instant invention and hence are not shown and will not be further described.

Control of the lift of the hydrofoil 11 in the embodiment shown is obtained by the deflection of a trailing edge flap 13 hingedly mounted on the hydrofoil 11 by hinge means 13'. It is apparent, however, that instead of using such flap means, the hydrofoil itself may be pivotally mounted on the strut 12 so that rotation of the hydrofoil about such pivotal mounting varies the lift characteristics of the hydrofoil. Thus, the invention requires only that there be at least a portion of the hydrofoil pivotally mounted such that rotation about such pivotal mounting varies the lift characteristics of the hydrofoil. Although the following description is confined to a description of an embodiment using flap means which are actuated by the control means to vary the lift of the hydrofoil, the use of the same control means to vary the angle of attack of the hydrofoil itself, or any portion thereof, for the same purpose is within the spirit and scope of this invention.

In the embodiment shown, the automatic control means used to actuate the flap 13 comprises an upwardly extending surface-piercing controller vane 14. Controller vane 14 consists of an elongated plate 15 and a drag element 16 which is mounted on the leading edge of the plate. Drag element 16 may be of V section, with the leading edge of plate 15 welded to the inside apex of the V as best shown in FIG. 1, or may be of any other suitable configuration or size to best serve its function. The lower end 17 of plate 15 is welded or otherwise suitably mounted on the upper surface 18 of flap 13. As a protective measure against waterborne debris, controller vane 14 may be mounted astern of and in alignment with the strut 12 as shown; however, it is obvious that the controller vane may be mounted in any other suitable location if design requirements so dictate.

In operation when the craft is getting under way, the controller vane 14 is fully immersed as shown in FIG. 2 and is subjected to high drag by the water. The drag forces exerted on the controller vane are sufficient to overcome the forces of the water acting upwardly against the bottom surface 31 of trailing edge flap 13, thus the vane is rotated counterclockwise to depress flap 13. With the flap in such position, the hydrofoil 11 will be in its configuration for producing maximum lift. The controller vane 14 will remain substantially submerged and maintain the hydrofoil in the high-lift configuration as the craft builds up speed, thus reducing the time required to attain foil-borne operation. As the speed increases, the lift generated by the hydrofoil system raises hull 10 of the craft out of the water so that the craft attains foil-borne operation. When strut 12 emerges from the water as the speed increases, the controller vane 14 also is carried upwardly to emerge from or "pierce the surface" of the water such that the area of the vane immersed in the water is reduced. A reduction in the area of the controller vane 14 immersed in the water reduces its drag and consequently reduces the forces exerted by the vane on the flap. The thrust of the water against the bottom of the flap, then being greater than the forces exerted by the vane on the flap, causes the flap to rotate upwardly until the forces again are in balance. The strut and along with it, the vane, will continue to emerge from the water until the craft reaches its predetermined "design" speed and height above the water as shown in FIG. 3. At this speed and height of the craft, the forces

on the flap are balanced and the system may be considered to be in equilibrium.

Should the actual submergence of the hydrofoil at design speed momentarily exceed design submergence such as by the craft encountering a wave or swell, the area of the controller vane under water will be increased. This increases the drag of the vane and the flap will be deflected downwardly thereby increasing the lift of the hydrofoil to restore it to design submergence. Hence the craft is raised to contour a wave or swell.

Conversely, should the actual hydrofoil submergence at design speed momentarily become less than design submergence as by encountering a trough, the area of the controller vane under water will be reduced. This decreases the drag of the vane and the water pressure acting against the bottom of the flap causes the flap to deflect upwardly. This in turn reduces the lift of the hydrofoil, causing a submergence to the design depth to contour the trough.

In the event the speed of the craft increases above the design speed, the control action is as described immediately above. The decrease in drag of the vane brought about by the progressive emergence of the hydrofoil and vane with increasing speed permits the flap to deflect upwardly which results in a reduction in hydrofoil lift. This decrease in hydrofoil lift causes the craft to settle to a lower level so that the controller vane submergence is at a level where the drag forces on the vane and on the flap balance out and again reach a condition of equilibrium.

When the craft encounters head seas, the closing speed of the craft with respect to those seas results in less time being available for the control system to respond. However, under these conditions, the upward component of the orbital velocities of such head seas in effect increases the angle of attack of the hydrofoil to accentuate the response to the control system. As described previously for the condition when the craft encounters a wave, the resultant forces exerted by the controller vane with the increase in submergence as the hydrofoil enters the wave, causes a deflection of the flap downwardly. This increases the lift of the main hydrofoil to enable the wave to be contoured.

In a following sea, there is, in effect, a decrease in the angle of attack of the hydrofoil as a result of the downward component of the orbital velocities of such following seas. This decrease in the angle of attack decreases the lift of the hydrofoil and increases its submergence into the water. However, this settling also results in the controller vane being immersed deeper in the water and the consequent build up in its drag increases the forces thereon so as to deflect the flap downwardly. As before, this increases the lift of the hydrofoil to avoid settling in a following sea.

In the foregoing description of the operation of our invention the discussion has been confined to a single hydrofoil with its controller vane although we recognize fully that craft of this type normally are equipped with more than one hydrofoil. It is apparent that when our invention is used with hydrofoil craft having two hydrofoils, either spaced athwartships on either side of the hull or in a tandem arrangement along the keel, automatic leveling of the craft will be provided in event some occurrence should alter the equality of submergence of the two hydrofoils. Such an occurrence might be, for example, a shift in the loading of the craft, although other factors such as wave action might tend to create such a condition. It will also be apparent that the automatic leveling just discussed is equally valid for roll in the athwartships hydrofoil arrangement and for pitch in the tandem arrangement.

In the discussion thus far, the controller vane acting automatically in conjunction with the flap has been treated as the sole means for the control of the hydrofoil. However, height control of the craft in foil-borne operation may also be achieved with the override control 19 shown

in FIG. 4 acting in conjunction with the controller vane. Referring to FIG. 4, the override control 19 is seen to consist essentially of a bellcrank 20 and a push-pull control cable 21 and requisite mounting hardware. Bellcrank 20 is pivotally mounted on strut 12 by means of a bracket 32 which is riveted or otherwise secured on the trailing edge of the strut. Bellcrank 20 pivots about and is fastened to bracket 32 by bolt 22. The lower arm of the bellcrank incorporates a cam portion 23 which may be brought selectively into operational engagement with the upper leading edge of controller vane 14. Cam portion 23 is suitably shaped to impart the desired rotational displacement to controller vane 14 upon rotation of bellcrank 20. Cam portion 23 may be provided with a facing 24 of a suitable elastomeric material to reduce wear and to dampen shock and vibration. Actuation of bellcrank 20 is by means of push-pull control cable 21 whose lower end is pivotally connected to the upper arm 25 of the bellcrank by a pin 26 and clevis 27. Pin 26 is secured in position by a suitable locking ring 28 and may be located in any one of the transverse holes 29 drilled in spaced relationship along the longitudinal axis of the upper arm 25 of the bellcrank. As may be clearly seen by referring to FIG. 4, the mechanical advantage of the control cable with respect to the bellcrank is governed by the position of the clevis pin 26 along arm 25 and may be adjusted as required. Clevis 27 is secured to the end of the control cable 21 in any well known manner as by barrel 30. The upper end cable 21 is connected to any suitable actuating means (not shown) for operating the cable to impart rotational movement to bellcrank 20.

Still referring to FIG. 4, the mechanical functioning of override control 19 may be readily ascertained. Movement of control cable 21 upwardly results in a clockwise rotation of bellcrank 20. This rotation, in turn, will impart a counterclockwise rotation to controller vane 14 when, in the course of the rotation of the bellcrank, cam portion 23 comes into contact with the controller vane. Should the control cable 21 be moved downwardly, bellcrank 20 is caused to rotate in a counterclockwise direction. This rotation relieves the pressure exerted by cam portion 23 on the controller vane 14, permitting the vane to rotate in a clockwise direction. Angular displacement of the controller vane, of course, results in a deflection of the hydrofoil flap 13 on which the vane is fixed. Counterclockwise displacement of the vane deflects the flap downwardly and clockwise displacement rotates the flap upwardly.

By using the override control, therefore, it is thus possible to override the automatic depth control system and to control collectively or selectively the depth of submergence of the hydrofoils such that a craft with athwartships disposed hydrofoils may be controlled in roll, pitch or height as for example, the craft may be banked into a turn and the like. In a craft having hydrofoils disposed in the fore-and-aft direction, the override control permits a selective control of the craft in pitch. The means used to operate the control cable which actuates the override control are not shown but it is clear such means may comprise a manually driven mechanism or any other suitable means now commonly available in the art.

Although shown and described in what is believed to be the most practical and preferred embodiments, it is apparent that departures from the specific apparatus shown will suggest themselves to those skilled in the art and may be made without departing from the spirit and scope of the invention. We therefore do not wish to restrict ourselves to the particular form of construction illustrated and described, but desire to avail ourselves of all modifi-

cations that may fall within the scope of the appended claims.

Having thus described our invention, what we claim is:

- 5 1. In combination, a hydrofoil including means mounting at least a portion of said hydrofoil for varying its lift characteristics, and a vane member rigidly mounted upon and extending upwardly from said lift varying portion of said hydrofoil and responsive to the drag forces of the water thereon for controlling the position of said lift varying portion.
  - 10 2. A hydrofoil craft including at least one downwardly depending strut member, a hydrofoil provided on said strut member and including means mounting at least a portion thereof for varying its lift characteristics, and a vane member rigidly mounted upon and extending upwardly from said lift varying portion of said hydrofoil and responsive to the drag forces of the water thereon for controlling the position of said lift varying portion.
  - 15 3. A hydrofoil craft including at least one downwardly depending strut member, a hydrofoil provided on said strut member and including means mounting said hydrofoil for varying its lift characteristics, and a vane member rigidly mounted upon and extending upwardly from said hydrofoil and responsive to the drag forces of the water thereon for controlling the position of said hydrofoil.
  - 20 4. A hydrofoil craft as defined in claim 2 wherein said lift varying portion comprises a flap hingedly mounted on the trailing edge of said hydrofoil.
  - 25 5. The combination set forth in claim 1 wherein said lift varying portion comprises a flap hingedly mounted on the trailing edge of said hydrofoil.
  - 30 6. In combination, a hydrofoil including means mounting at least a portion of said hydrofoil for varying its lift characteristics, and a surface-piercing controller vane rigidly mounted on and extending upwardly from said lift varying portion and adapted to deflect said lift varying portion in response to the drag forces of the water acting on said controller vane.
  - 35 7. A hydrofoil craft comprising a hull, at least one downwardly depending strut secured to said hull, a hydrofoil provided on the lower end of said strut and including means mounting at least a portion of said hydrofoil for varying its lift characteristics, a controller vane rigidly mounted on said lift varying portion of said hydrofoil and extending upwardly with its upper end portion piercing the water surface when the craft is in foil-borne operation and adapted to deflect said lift varying portion in response to the drag forces of the water acting on said controller vane.
  - 40 8. A hydrofoil craft as defined in claim 7 and including selectively operated control means adapted to engage the upper end portion of said controller vane.
  - 45 9. A hydrofoil craft as defined in claim 7 and including a bellcrank pivotally mounted on said strut, and actuating means connecting one arm of said bellcrank, the other arm of said bellcrank being adapted to engage the upper end portion of said controller vane.
